SEWING MACHINE

Otto R. Haas, North Beverly, Mass., assignor to
 United Shoe Machinery Corporation, Paterson,
 N. J., a corporation of New Jersey

Original application March 19, 1932, Serial No.
 600,016. Divided and this application March
 1, 1935, Serial No. 8,863

12 Claims. (Cl. 112—219)

The present invention relates to shoe machines and is herein set forth as embodied in an outsole stitcher of the type in which the shoe and the stitch forming devices are moved relatively 5 to transfer the point of operation about the shoe and to change the relative positions of the shoe and the operating means to present the shoe properly to the operating means as the point of operation is transferred about the shoe, and in 10 which the shoe is supported in operating position in the machine and all of its movements are effected and controlled by automatically acting mechanisms. A machine of this type is disclosed in applicant's prior application Serial No. 15 600,016, for Shoe sewing machines, filed March 19, 1932 of which the present application is a division.

The primary object of the present invention is to improve the construction and mode of operation 20 of outsole shoe sewing machines and to produce a machine of the automatic type above referred to which is more efficient, reliable and uniform in its operation than prior machines, and upon which an operation on a shoe may be 25 successfully performed by a comparatively unskilled operator with a minimum expenditure of labor and time. Certain features of the invention may be utilized to advantage in connection 30 with shoe sewing machines other than outsole stitchers or in connection with machines for performing other shoe making operations. Also, certain features are not limited to use in machines which are wholly automatic in character, but may be embodied in machines in which at 35 least some of the required relative movements of the operating instrumentalities and shoe are produced or controlled by the operator.

The automatic machine hereinafter described 40 is of that type which comprises a jack upon which the shoe to be operated upon is supported and to which positioning movements are imparted to cause the shoe to be presented properly to the operating means as the point of operation is transferred about the shoe.

One feature of the present invention embodied 45 in the machine hereinafter described comprises an improved means for stopping the machine in case of a misstitch caused by slack or broken thread. In the present form of this feature of the invention, the machine, having a thread cutter and mechanism for throwing the jack out of operative position as the seam is completed on a shoe, is arranged with electrically controlled 50 devices to prevent actuation of the thread cutter

and throwing out of the jack when the machine is stopped by reason of a misstitch.

The circuits of the electrically controlled devices according to the illustrated embodiment of the invention, are rendered inoperative to stop the machine just before the seam is completed and for the first few stitches on a new shoe so that slack thread due to causes incident to stopping or starting will not effect the proper operation of the machine. 10

The features of invention above referred to and other novel constructions, combinations and arrangements of parts hereinafter described and claimed will be readily understood by those skilled in the art from the following description 15 taken in connection with the accompanying drawings which illustrate an automatic outsole stitcher constituting one specific embodiment of the several features of the invention.

In the drawings Figure 1 is a view in front 20 elevation of a complete automatic outsole stitcher embodying the several features of the invention with the lower portion of the main base, the motor, and certain other parts broken off; Figure 2 is a plan view of the machine with the 25 frames for the power drive and sewing mechanism removed, and with the base partly broken away to show the construction and mechanism within the base; Figure 3 is a view in elevation of the upper portion of the machine from the 30 right side, partly in section, illustrating particularly the driving and stopping mechanism; Figure 4 illustrates diagrammatically a wiring system for electrically connecting various parts of the machine; Figure 5 is a view on an enlarged 35 scale of a portion of the sewing mechanism in the machine; and Figure 6 is a detail view showing, in side elevation and section, certain of the parts connected with the driving and stopping mechanism. 40

Referring to Figures 1 and 2 of the drawings, the frame of the machine comprises a main base 2 having a horizontal top 4. Suspended through an opening in the top is a cradle 6, machined to carry the frames 8 and 10 for the power drive 45 and the sewing mechanism, respectively. The power drive frame 8 supports a driving motor 12 attached to a flange at the top of the machine.

The motor 12 is mounted to drive a vertical shaft 14 (see Figs. 3 and 6) for operating the 50 constantly rotating main power driver, indicated at 16. The power driver 16 is formed at its lower portion with a conical clutching surface 18 for engaging a correspondingly shaped internal clutching surface 20 on a driven clutch 55

member 22. The clutch member 22 extends upwardly from a sleeve 23 freely slideable and rotatable on a shaft 24 and provided with an integrally formed helical gear 25 at its central portion for driving a sewing cam shaft and a pattern cam shaft of the machine. The driven clutch member 22 is held in engagement with the clutching surface of the power driver by a heavy compression spring 26 between the sleeve 10 23 and a bearing carried by the power drive frame. The outside surface of the driven clutch member is also conical in shape and is adapted to engage an annular braking member 27 attached to the frame of the machine.

15 To disengage the driven clutch member from the main driver at the proper time and wedge it within the braking member 27 to arrest the movement of a sewing cam shaft 28 and a pattern cam shaft 29 driven thereby, means substantially the same as in the driving and stopping mechanism described in the U. S. Patent to Topham No. 1,791,176 granted February 3, 1931 are provided, comprising a suitably shaped cam slot 30 formed on the sleeve 23 for engagement with a spring pressed lock bolt 31. The lock bolt is mounted in a carrier 32 rigidly secured to a horizontal rock shaft 34 mounted in the frame.

While the machine is in operation and while 30 the sewing and pattern cam shafts are being driven, the lock bolt 31 is out of engagement with the cam slot 30 and the clutch member 22 is held in engagement with the power driver 16 by the force exerted by the spring 26 on the sleeve 23. To disengage the driven clutch member from the power driver, the lock bolt is allowed to engage the cam slot 30 in the sleeve 23 and at a certain point in the revolution of the sleeve the carrier for the bolt is held against 35 movement, thereby causing the lock bolt and cam groove to cooperate in forcing the clutch member 22 away from the power driver against the force of the spring 26, and bringing the brake surface on the driven clutch member into engagement with the fixed braking member 27. The horizontal arm of the carrier in which the bolt is mounted is maintained in raised position by a spring 35 stretched between the vertical arm of the carrier and the frame of the machine. When the locking bolt is allowed to move toward the cam slot, it engages the outer 40 surface of the sleeve 23 and slides into the slot when the slot registers with the bolt. Continued rotation of the clutch member causes the lock bolt to be moved downwardly and the lock bolt carrier to be moved in a clockwise direction. Movement of the lock bolt in the opposite direction is then prevented by the engagement of the vertical arm of the lock bolt carrier by a 45 spring pressed latch 36. The lock bolt carrier with the lock bolt 31 is thus held against movement and the continued rotation of the sleeve 23 causes the separation of the clutch members.

To start the machine in operation a power 60 operated starting mechanism is provided comprising a horizontal crank shaft 38 and an auxiliary one-revolution clutch 40 on the shaft. The one-revolution clutch is ordinarily held in uncoupled condition by an abutment 42 (see 65 Fig. 6) carried on a rod 44 pivoted to the machine frame. To enable the crank shaft to be operated, the one-revolution clutch is coupled by rocking the abutment 42 out of contact with the clutch. The abutment 42 is rocked by means 70 of a manually operated handle 46 pivoted on the

frame. Rotation of the crank shaft actuates the lock bolt 31 and the carrier latch 36 to free the main driven clutch member 22 from engagement with the stationary brake and allow it to rise under the pressure of the compression 5 spring, into driving relation with the lower driver 16, the crank shaft 38 carrying a pitman 48 with a vertically adjustable stop screw 50. The latch 36 is released from the lock bolt carrier and the lock bolt 31 is withdrawn from engagement with the cam slot 30 by the action of the stop screw 50 on a projecting screw 54 carried by a link 56 through connections substantially the same as disclosed in Patent No. 1,791,176. 15

The mechanism for automatically initiating the final stopping movements of the machine is actuated from the pattern cam shaft 29 after it has nearly completed a revolution. This mechanism acts to release the lock bolt 31 and permit it to move into engagement with the cam slot 30 of the main clutch member 22 and is substantially the same as the mechanism disclosed in Patents No. 1,791,176 and No. 1,834,471. This mechanism (see Figs. 2 and 4) comprises a gear 25 57 at the upper end of the pattern cam shaft and a block 58 secured to the upper surface of the gear, which block, after the pattern cam shaft has made nearly a complete revolution, engages and swings backwardly a pawl lever 60, 30 and through the pawl moves a lever 62 pivotally mounted at 64 on the machine frame. A sliding rod 66 is pivotally connected at its rear end to the lever 62 and at its forward end is arranged to engage the end of a dog 68 pivotally mounted 35 at the left hand end of a lever 70. The arrangement of these parts is such that as the pattern cam shaft nears the end of a revolution the lever 62 is rocked, the rod 66 is moved longitudinally towards the front of the machine, and the lever 70 is swung forwardly at its left hand end about its pivot 72. The right hand end of the lever 70 is connected by means of a slotted link 74 to the left hand end of another short centrally fulcrumed lever 76. The right hand 40 end of the short lever is provided with a V-shaped recess in which the lower wedge shaped end of a vertical sliding control bar 77 rests (see Figs. 1 and 2). When the left hand end of lever 72 is moved forwardly, the right hand 45 end of the short lever 76 is actuated to raise the vertically sliding control bar 77. When the control bar is given an upward movement, the lock bolt 31 is permitted to engage the cam slot 30 on the main driven clutch member. The entry 50 of the lock bolt 31 within the cam slot 30 causes the driven clutch member to become disengaged from the main driver and wedge within the braking member 27 to arrest the movement of the main sewing cam shaft. 60

The jack 78 and its supporting structure are substantially the same as in the machine of Patent No. 1,834,471, more fully described in U. S. Patent to Laurence E. Topham and Alfred R. Morrill No. 1,616,714, dated February 8, 1927 65 and in applicant's co-pending application, above referred to. During the sewing operation, tipping and rotating movements are imparted to the shoe to maintain the shoe at all times in proper position, tipping movements being imparted by moving the lower end of the jack forwardly and rearwardly of the machine, and laterally, and rotating movements being imparted by rotating the jack about the axis of the jack. In the present machine, the shoe is fed by the devices 70 75

of the sewing mechanism acting directly on the shoe.

When the sewing mechanism is brought to rest at the end of a seam by disconnecting the main driven clutch member 22 from the main driver, an auxiliary mechanism similar to that of the machines of Patents No. 1,616,714 and No. 1,834,471 is automatically connected to the main driver 16 in substantially the manner disclosed in said patents. This mechanism comprises an eccentric 79 (see Fig. 6) mounted to turn loosely upon a hollow stud formed on the machine frame below the motor shaft 14. Vertically below the eccentric 79 is a clutch block 80 arranged to drive the eccentric whenever the lever 70 is swung forwardly by the connections to the cam shaft in actuating the vertical sliding control bar 77 to stop the machine. This auxiliary mechanism actuated by the eccentric 79 includes an eccentric strap 82 by which the jack is moved outwardly away from the sewing devices, and also the mechanism through which a movement is imparted to the pattern cam shaft to complete its rotation so as to cause the jack to be reversely rotated to its initial position. Other operations performed during the final stopping movements of the machine include actuating a thread cutter 84 (see Fig. 3) to sever the threads of the last completed stitch and releasing the grip on the projecting edge of the shoe sole of the work support and the presser-foot. The thread cutter for severing the threads is operated from a continuously driven mechanism and includes a momentarily actuated one-revolution clutch 86. The same clutch also operates mechanism for releasing the presser-foot from engagement with the shoe sole.

The stitch-forming devices (see Figs. 3, 4 and 5) include the curved hook needle, indicated at 88, the awl at 90, the work support at 92, the presser-foot at 94, the shuttle at 96, the looper at 98, the main take-up at 100, the auxiliary take-up at 102, the thread tension wheel at 104 and other mechanisms. In order to insure that the needle thread will not be pulled from contact with a new shoe as the first stitch is being formed, means is also provided for rotating the tension wheel 104 to withdraw a length of thread from the supply prior to the formation of the initial stitch when the machine is started, as described more fully in applicant's copending application.

The means for stopping the machine in case of a misstitch, according to the present invention, (see Figs. 4 and 5) is actuated by the relative positions of the main and auxiliary take-up members 100 and 102, and comprise contact members 106 fixed in insulating material carried by a fulcrum shaft 108 on which the main take-up member 100 is operated. The auxiliary take-up member 102 is carried on the shaft 108 which passes loosely through a hub portion 110 of the auxiliary take-up member. Also, extending from the hub 110 is an arm 112 carrying a double ended spring contact 114 separated from the end of the arm by insulating material. The two contact members 106 are provided with arcuate surfaces for forming a rubbing contact with spring supported brushes 116 insulated from the frame of the machine and connected to wires 118 and 120, respectively. The contact members 106 are fashioned with radial shoulders 122 to which are attached contact points 124 of suitable refractory metal to cooperate with corresponding points on the two ends of the spring contact 114. Movements of the contact 114 and

the contact members 106 together complete the connections from wire 118, through the corresponding brush 116, the contact member 106, the spring contact 114, the other member 106 and back through the wire 120 by the corresponding brush 116. The completion of the circuit through these connections actuates electrical apparatus hereinafter described to stop the machine without actuating the thread cutter or throwing the jack out of operative position in the machine and thus indicates slack thread due to breakage or other cause.

The main take-up member is operated from the main sewing cam shaft by oscillation of fulcrum shaft 108 which shaft has suitable bearings in the sewing machine frame. The auxiliary take-up member 102 is operated in one direction by a spring 128, stretched between a right angle arm 130 extending from the hub of the auxiliary take-up member and the frame of the machine. A stop is provided for the auxiliary take-up member in the form of an adjustable abutment screw 132 threaded into the sewing frame for preventing extreme movement of the auxiliary take-up member during the operation of the machine. The abutment screw is so adjusted that with the auxiliary take-up released to its extreme position under the action of spring 128, the contact members 106 operated by the main take-up will just contact with the double ended spring contact 114 operated by the auxiliary take-up at the extreme position occupied by the main take-up. The auxiliary take-up may strike the abutment screw 132 at any other point during the stitch-forming cycle of operations without completing the circuit through the contacts. At the time when each stitch is set the thread extends in a substantially straight line between a stationary pulley (not shown) and a pulley 134 rotating loosely on the fulcrum shaft 108, with the auxiliary take-up resting on this straight portion of thread. The thread is subject to the greatest tension at this time and the auxiliary take-up member is also in its most forward position. If breakage or slack thread from other cause occurs at this time, the circuit between the contacts will be closed and the machine brought to rest.

The electrical apparatus connected with contacts 106 for stopping the machine upon the occurrence of a misstitch is illustrated diagrammatically in Figure 4. The wires 118 and 120 connected to the brushes 116 are connected to one terminal of the low voltage winding of a transformer 136 and to a relay 138. The relay 138 is connected by a wire 149 to a stationary contact 142 positioned to be acted upon by a movable contact 144. The movable contact is connected to the other terminal of the low voltage winding of the transformer 136 by a wire 146. When the circuit is closed through contacts 142 and 144 and through the contacts 106 and 114, the relay 138 is energized, closing relay contacts 148 having a connection 150 to one side of a source of power 152. A connection 154 from the other side of the source of power 152 completes the circuit through a solenoid 156. Thus, when the coil circuit of the relay 138 is completed, the solenoid 156 will be energized to retract its armature 158. The solenoid 156 is bolted at 160 to the right-hand edge of the base of the machine, adjacent the V-notched end of the short lever 76 for actuating the control bar 78 (see Figs. 1, 2 and 4), to bring the machine to rest. The armature 158 of the solenoid 156 is pivotally connected to a hooked member 162. The forward end of the

hooked member is provided with a notch to co-operate with a detent 164 fixed to a shaft 166 which is journaled in a bracket 168 extending from the base of the machine and attached to the frame of the solenoid. At the lower end of the shaft carrying the detent, an arm 170 acts on the notched end of the short lever 76 to move it forwardly when the magnet 156 is energized and to raise the control bar 71. Movement of the lever 76 moves the link 74 toward the rear of the machine. The connection between the link 74 and the lever 70 is a pin and slot so that the slotted end of the link slides idly without actuating the lever 70 to cause the operation of the auxiliary clutch block 80, as previously described. Since no movement of these levers is produced, the auxiliary clutch for completing the movement of the jack and pattern cam shaft is not thrown into operation and the jack remains in operative position with the sewing mechanism, when the machine is stopped by energizing the solenoid 156. As the armature 158 is retracted, a positioning pin 172 fixed in the bracket 168 and sliding in an oblique slot 174 in the hooked member 162 acts to throw the free end of the hooked member away from the end of the detent 164 to permit the lever 76 to return to its original position. When the solenoid is deenergized, a spring (not shown) presses the armature 158 out of the coil and a spring 176 causes the hook member 162 to snap in front of the detent 164 ready for another operation.

The thread cutter 84 is arranged to be actuated only at the end of the outseam, at which time the sewing mechanism has reached the breast line of the heel and the pattern cam shaft has substantially completed its rotation. To secure this result, the lever 62 operated by the block 58 on the pattern cam shaft is provided at its left hand end with a pivotal connection to a link 178 pivotally connected at its forward end to a lever (not shown) for controlling the thread cutter. The thread cutter clutch may, by this connection, be coupled to cut the thread and release the shoe from the stitch-forming devices only when the pattern cam shaft has nearly reached its stopping position.

Means is also provided for preventing the operation of the thread break solenoid 156 upon the occurrence of slack thread during the first few stitches on a new shoe and during the final movements of the machine. To this end the block 58 on the pattern cam shaft for operating the stop motion is arranged to strike the end of a lever 180 fulcrumed at 182 on the frame of the machine and pivotally connected to a lever 184 by an intermediate link 186, extending through an opening in the casing of the base of the machine. The lever 184 is mounted to rock about a supporting shaft 188 fixed to a bracket 190 attached to the rear of the base and operates a second lever 192, also pivoted on the shaft 188, through a spring 196 connecting lugs on the two levers and yieldingly holding a set screw 198 mounted in a lug on the lever 184 in contact with a lug on lever 192. The lever 192 carries the insulated contact 144 and is normally held in a position in which the contact 144 engages the contact 142, insulated from the bracket 190 by a spring 200 stretched between the lever 184 and the frame of the machine. The wires 140 and 146 are connected, respectively, to the contacts 142 and 144 and lead through an armored cable or other suitable conduit to a box 202 in which the various circuit connections are made. During the final

movements of the pattern cam shaft, the lever 180 is moved rearwardly by the block 58, breaking the circuit to the relay 138 by separating the contacts 142 and 144. Should a thread break occur at this time and the contacts 106 and 114 be moved together the relay 138 will not be energized nor the armature 158 be retracted. The contacts 142 and 144 are caused to remain separated during the first few stitches on a new shoe by positioning the end of the lever 180 so that it will not be relieved from the block 58 immediately upon starting the machine. If the contacts 106 and 114 should come together during the first few initial stitches, an account of slack thread produced by rotation of the tension wheel, the machine will not be stopped because the controlling circuit of solenoid 156 is maintained open by contacts 142 and 144.

The nature and scope of the present invention having been indicated and a machine embodying the several features having been specifically described, what is claimed is:

1. A sewing machine having, in combination, stitch-forming devices including an oscillatory main thread take-up, an auxiliary take-up, a member movable with said auxiliary take-up, a member movable with said main take-up arranged to contact with the member movable with the auxiliary take-up at one limit of movement in the travel of said main take-up, and means for stopping the machine rendered operative by the contacting of said members by reason of slack thread.

2. A sewing machine having, in combination, stitch-forming devices including an oscillatory main thread take-up, an auxiliary take-up, yielding means for forcing said take-ups together, and means for stopping the machine comprising electrical contacts movable with said take-ups to complete a circuit as said take-ups are forced together by reason of slack thread under the action of said yielding means.

3. A sewing machine having, in combination, stitch forming devices including an oscillatory main thread take-up, an auxiliary take-up, yielding means for forcing said take-ups together, an abutment for preventing contact of said take-ups except in extreme position of said main take-up, and means for stopping the machine comprising electrical contacts movable with said take-ups to complete a circuit as said take-ups are forced together by reason of slack thread under the action of said yielding means.

4. A sewing machine having, in combination, stitch-forming devices including an oscillatory main thread take-up, an auxiliary take-up, electrical contacts arranged to be engaged by the joint movement of said take-ups, yielding means for moving said take-ups to engage the contacts upon a misstitch, an electric circuit including an electro-magnet controlled by said contacts, apparatus for stopping the machine controlled by said electro-magnet and a switch connected in said circuit for rendering said contacts ineffective for operating said apparatus during a predetermined initial movement of said stitch-forming devices.

5. A shoe machine having, in combination, means for operating upon a shoe, a shoe supporting jack, mechanism for changing the relative positions of the shoe and the operating means to present the shoe properly to the operating means as the point of operation is transferred along the shoe, an electric circuit including an electro-magnet controlled by said operating means, apparatus for stopping the machine connected to 75

5 said electro-magnet, and contacts associated with said position changing mechanism to render said circuit ineffective for operating said electro-magnet during a predetermined initial movement of said jack.

6. A shoe sewing machine having, in combination, stitch-forming devices comprising a main thread take-up and an auxiliary take-up, electrical contacts operable to affect a circuit by joint movement of said take-ups to an extreme position in the travel of each, an electro-magnet contained within the circuit including said contacts, apparatus for stopping the machine connected to said electro-magnet, a shoe supporting jack, mechanism for changing the relative positions of the shoe and the stitch-forming devices to present the shoe properly to the stitch-forming devices as the point of operation is transferred along the shoe, and contacts associated with said jack position changing mechanism to render said circuit ineffective for operating said electro-magnet during a certain portion of the travel of the jack.

7. A sewing machine having, in combination, stitch-forming devices, a main thread take-up for setting the stitch, an auxiliary thread take-up to maintain tension on the thread and contacts engageable upon release of said auxiliary take-up through thread breakage or the like, to close a circuit by the joint action of said take-ups while said main take-up is in stitch-setting position.

8. A sewing machine having, in combination, stitch-forming devices, a main thread take-up for setting the stitch, an auxiliary thread take-up to maintain tension on the thread, contacts engageable upon release of said auxiliary take-up through thread breakage or the like to close a circuit by the joint action of the take-ups while the main take-up is in stitch-setting position, and means for preventing engagement of the contacts when the main take-up is in any other than stitch-setting position.

9. A sewing machine having, in combination, stitch-forming devices, a main thread take-up for setting the stitch, an auxiliary thread take-up to maintain tension on the thread, contacts engageable upon release of said auxiliary take-up through thread breakage or the like to close a circuit by the joint action of the take-ups while the main take-up is in stitch-setting position, and a stop arranged to hold the auxiliary take-up in a position where the contacts will be out of engagement when the main take-up is in any other than stitch setting position.

10. A shoe machine having, in combination, means for performing a principal operation on a shoe, a shoe supporting jack, a pattern cam shaft, mechanisms actuated by the cam shaft for changing the positions of the shoe and the operating means to present the shoe properly to the

operating means as the point of operation is transferred along the shoe, mechanism for causing the machine to perform certain auxiliary operations after the principal operation is completed, a driving and stopping mechanism for the machine, a control lever for the driving and stopping mechanism actuatable in one direction to stop the machine and set the auxiliary mechanism into operation and in the other direction to stop the machine only, connections between the pattern cam shaft and the control lever for actuating the lever in the first direction, and other connections between the operating means and the control lever for actuating the lever in said other direction whenever the operating means 15 operates improperly.

11. A shoe sewing machine having, in combination, stitch forming devices, a shoe supporting jack, a pattern cam shaft, mechanisms actuated by the cam shaft for changing the positions of the shoe and operating means to present the shoe properly to the operating means as the point of operation is transferred along the shoe, mechanism for causing the machine to perform certain auxiliary operations after the stitching is completed, a driving and stopping mechanism, a control lever for the driving and stopping mechanism actuatable in one direction to stop the machine and set the auxiliary mechanism into operation and in the other direction to stop the machine only, 20 connections between the pattern cam shaft and the control lever for actuating the lever in the first direction, and other connections between the stitch-forming devices and the control lever for actuating the lever in said other direction 30 whenever the stitch-forming devices operate improperly.

12. A shoe sewing machine having, in combination, stitch-forming devices, a shoe supporting jack, a pattern cam shaft, mechanisms actuated by the cam shaft for changing the positions of the shoe and operating means to present the shoe properly to the operating means as the point of operation is transferred along the shoe, mechanism for causing the machine to perform certain auxiliary operations after the stitching is completed, a driving and stopping mechanism, connections between the auxiliary mechanism, the driving and stopping mechanism and the cam shaft for actuating said mechanisms at the end 45 of a seam, other connections between the stitch-forming devices and the driving and stopping mechanism for bringing the machine to rest whenever the stitch-forming devices operate improperly, and means actuated by the pattern cam 50 shaft just before the seam is completed to prevent stopping of the machine from improper operation of the stitch-forming devices.

OTTO R. HAAS.
